COIN BANK

Filed Jan. 11, 1929

Inventor
Abraham J. Kusel
My Zabel & Banning Atty.

UNITED STATES PATENT OFFICE

ABRAHAM J. KUSEL, OF CHICAGO, ILLINOIS, ASSIGNOR TO BANKERS THRIFT CORPORATION, OF CHICAGO, ILLINOIS, A CORPORATION OF ILLINOIS

COIN BANK

Application filed January 11, 1929. Serial No. 331,756.

My invention relates to small coin banks and more particularly to a bank of this character which in appearance greatly resembles a toy barrel. It is a purpose of this invention to provide means whereby such banks may be constructed of a wooden body portion and an end closure secured therein in such manner as to avoid danger of breakage due to contraction and expansion of the wooden parts under changes in the weather conditions. It has been proposed heretofore to provide such banks with a wooden tubular body portion and then to secure at the opposite ends thereof flanged end closures by means of pressing them into the ends of the wooden barrel so that the friction of the wood upon the metal enclosures would hold them in place. Glue has also been used in this connection to aid in holding the end closures in position. This structure, however, does not work out well in practice owing to the fact that, if the end closures fit tightly within the ends of the tubular wooden body, they necessarily exert a considerable outward pressure tending to spread the wood. In the first place this results in a great amount of breakage in the manufacture thus increasing the cost of production; and in the second place, after the banks are put out in use, the contraction and expansion of the wood when it is dry or damp often times causes the wood to split or the heads to become loose in which case the utility of the bank is lost.

It is a principal purpose of this invention therefore to provide means whereby the end closures may be fitted within the opposite ends of the wooden body portion with a sufficient amount of play to prevent their exerting an outward disruptive force upon the barrel.

It is also a purpose to provide an improved method of assembly of such a device whereby all of the parts may be properly secured in position without any difficulty in performing the operations within the wooden body. Other and more specific objects and advantages of the invention will appear as the description proceeds in connection with the accompanying drawing wherein the pre-

ferred form of the invention is shown. However, it is to be distinctly understood that I do not intend to limit myself to the exact details shown and described but that I intend to avail myself of all such modifications as would occur to one skilled in this art and as fall within the scope of the claims.

In the drawing:

Fig. 1 is a vertical section through a toy barrel bank showing my improved means for securing the end closures in position;

Fig. 2 is a vertical section taken at right angles to Fig. 1;

Fig. 3 is a perspective view of the elements for securing the end closures in position and the end closures combined therewith; and

Fig. 4 is a top plan view of the bank shown in Fig. 1.

Referring now in detail to the drawing, the numeral 5 indicates the wooden body portion of the bank which is formed to imitate a barrel in exterior appearance and which has a substantially cylindrical interior wall 6. At the opposite ends of this broken body portion the bore is enlarged as at 7 and 8 to form enlarged recesses adapted to receive the end closures 9 and 10 which have the annular flanges 11 and 12 projecting toward each other and fitting down upon the shoulder provided by the enlarged bore 7 and 8. Top closure 9, as shown, is provided with a coin inlet slot at 13 and carries suitably pivoted baffle plates indicated at 14 and 15 which are adapted to permit the insertion of coins while preventing them from falling out through the apertures 13.

The end closure 10 is provided with a detachable head 16 which head is locked in place by means of the outwardly extending member 17 adapted to engage underneath the rim 18 on head 10 at one point and a key controlled locking jaw 19 adapted to engage under the flange 18 at the point directly opposite to the member 17, the key being adapted to be inserted at 20 to retract the locking jaw 19 when it is desired to open the bank and remove the contents. The details of this locking mechanism are not shown as they form no part of the present invention and may be of any well known type.

The end closures 9 and 10 fit rather loosely within the recesses 7 and 8 in order to prevent them from exerting an outward force which would tend to split the wooden body 5, since it has been found in practice that by a very tight fit in this point a great number of barrels will break down after they are put out in service either because the tight fit exerts too much pressure when the barrel begins to shrink and splits the barrel, or because the weight of the coins when they are shaken around in the barrel is sufficient to loosen the end pieces and cause them to fall out. I therefore, secure these end closures together by means which lie wholly within the barrel and therefore do not present any unsightly appearance on the exterior thereof.

This novel means consists of the members 21 and 22 extending between the end closures 9 and 10 and connected thereto so as to prevent the closures from moving away from each other. These members 21 and 22 are preferably metallic strips and are bent intermediate their ends so as to conform in curvature to the interior wall 6 of the body 5. The purpose of making them of this form is to permit them to lie flat against the wall 6 so that the coins within the bank cannot possibly become wedged behind them and so that they take up very little space in the coin holding chamber.

At the opposite end these strips 21 and 22 are provided with apertures as indicated at 23 and 24 and lips as indicated at 25 and 26 struck out from the material of the flanges 11 and 12 so that the apertures 23 and 24 may be hooked over these lips and the lips thereafter bent down in the position shown in Fig. 1 so as to lock the strips firmly to the end closures.

In assembling the device it is necessary to avoid difficulties, to proceed with the assembly in a certain definite manner which will now be described.

The barrel body 5 is first turned up in the lathe and provided with the recesses 7 and 8 and then the strips 21 and 22 are secured to the end closure 9 before the same is inserted in the body 5. After this has been done, strips 21 and 22 are inserted into the body 5 from one end so as to pass therethrough until the flange 11 is seated within the recess 8. The end closure 10 then has the detachable head 16 removed therefrom and is inserted within the recess 7. After this has been done, the strips 21 and 22 can be secured to the corresponding lips 26 on the closure 10 and these lips in turn bent down to tightly secure end closure 10 within the barrel. The barrel is then ready for use and the detachable head 16 may be replaced to complete the operation.

Having thus described my invention, what I claim as new and desire to secure by Letters Patent is:

1. An article of the character described comprising a tubular body portion of wood, a plurality of end closures having flange portions fitting within the ends of said body portion and means for holding said end closures in position comprising a plurality of metallic members connecting said closures within said body portion, said members comprising thin strips lying against the inner wall of said body portion and having their ends secured to said flange portions. 70

2. A device of the character described comprising a tubular barrel-shaped wooden body, said body having recesses at the opposite ends thereof, metallic end closures loosely fitted 80 within said recesses, and means for holding said end closures in said recesses comprising means extending from one end closure to the other and secured to both within said body, said means lying closely against the inner 85 wall of said body throughout the length thereof.

3. A device of the character described comprising a tubular barrel-shaped wooden body, said body having recesses at the opposite 90 ends thereof, metallic end closures loosely fitted within said recesses, and means for holding said end closures in said recesses comprising means extending from one end closure to the other and secured to both within 95 said body, said last named means comprising thin metal strips fitting flat against the inner wall of said body.

4. A device of the character described comprising a tubular barrel-shaped wooden body, 100 said body having recesses at the opposite ends thereof, metallic end closures having flanges fitting within said recesses, and metal securing strips within said body connecting said flanges. 105

5. A device of the character described comprising a tubular barrel-shaped wooden body, said body having recesses at the opposite ends thereof, metallic end closures, having flanges loosely fitting in said recesses, said 110 flanges having portions struck out therefrom and metal securing strips extending between said flanges and secured to said portions.

6. A coin bank comprising a tubular body portion of wood, end closures for said body 115 portion, one of said closures having a removable head and one of said closures having a coin inserting slot therein, and means for retaining said end closures in position comprising members in said body extending between said end closures and connecting the same; said members comprising metallic strips lying flat against the wall of said body. 120

7. A coin bank comprising a tubular body portion of wood, end closures for said body portion, one of said closures having a removable head and one of said closures having a coin inserting slot therein, and means for retaining said end closures in position comprising members in said body extending be- 125 130

tween said end closures and connecting the same, said members comprising metallic strips lying flat against the wall of said body, said end closures having flanges thereon provided with struck out portions to which said members are attached.

In witness whereof, I hereunto subscribe my name this 4th day of January A. D., 1929.

ABRAHAM J. KUSEL.
